SHEET METAL SCRIBING TOOL

John P. Patterson and Floyd Clemons, Tallahassee, Fla.
Application June 5, 1956, Serial No. 589,409

2 Claims. (Cl. 33—44)

The present invention relates to a special purpose hand tool which is expressly constructed and novelly designed to serve the requirements of a sheet metal worker or other user in scribing, marking, and denoting fold lines when laying out a sheet metal blank which is to be subsequently transformed into an auxiliary duct connectible with a primary duct or so-called trunk-line.

Stated otherwise, the invention pertains to a simple, expedient and practical hand tool susceptible of ready usefulness in sheet metal work in the laying out of patterns. That is to say, by the use of this tool it is possible to scribe or mark three lines on a sheet metal blank at the same time and in one operation. In this connection it is to be pointed out that it was the current practice, prior to the advent of the improved tool, to mark off three spaces with a ruler adjacent to the marginal edge of the blank which was being used. Then one draws or pencils the lines with the aid of a straightedge. This may be said to be the standard lay out practice in the procedure of providing either a prefabricated or an on-the-job so-called "tap-in," that is, the aforementioned auxiliary duct with its end flanged so that it can be connected with an opening tapped in one of the side walls of the trunk-line.

An object of the invention is to provide a scribing or marking tool which greatly expedites the steps which may now be pursued resulting in a great saving in time, labor and money.

Other objects, features and advantages will become more readily apparent from the following description and the accompanying sheet of illustrative drawings.

In the drawings:

Fig. 1 is a perspective view of the improved scribing tool;

Fig. 2 is a fragmentary plan view of an end portion of the blank which is being, or has been, scribed after having used the scribing tool (at the right) here depicted;

Fig. 3 is a view in plan based on Fig. 2 and showing what the blank looks like after the marked edge has been notched or cut out to define bendable flaps; and

Fig. 4 is a sectional view showing the main duct or trunk-line and the auxiliary "tap-in" connected to the apertured wall thereof in a well-known manner.

Referring first to Fig. 4 the trunk-line or main duct is denoted by the numeral 6 and has a tapped opening or hole in one side wall as at 8 with which the auxiliary duct or so-called "tap-in" 10 is connected. The "tap-in" is provided at its connectible end with the usual cooperating several flanges 12, 14 and 16. These require the provision of fold or marker lines to provide the required bends 18. Fig. 2 shows the blank and Fig. 3 the next step wherein it has been notched to provide the flaps 20. The blank is also folded along the lengthwise lines 22 to provide the construction shown in Fig. 4.

The idea here is centered on the hand tool and this comprises a block-like body 24 preferably rectangular and having a flat side 26 carrying rigid laterally projecting spaced parallel prongs 28 having coplanar needle-like terminals or scribing ends 30. These, when properly raked or moved across the surface of the blank 32, seen in Fig. 2, provide the scribed lines 34, 36 and 38 in measured spaced parallel relationship. To the right there is an integral cylindrical rigid abutment finger 40 having a laterally directed bend or hook 42 which assists in retaining the tool in position while it is moved along the edge 44 in an obvious manner.

2
The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

- 10 1. For use by a sheet metal worker or one engaged in scribing and laying out a sheet metal blank which is to be subsequently transformed by bending and forming into a duct having a specially flanged end and which is to be tapped into an opening provided therefor in a trunk-line; a measuring and scribing hand tool comprising a body functioning as a handle and having a plurality of rigid duplicate spaced parallel needle-like scribing prongs projecting laterally from one surface of the body and which cooperatively function in unison and in a manner to score and visibly mark the surface of the blank with spaced parallel flange-forming fold-lines, and a guiding abutment integral with and projecting laterally from said one surface, said abutment comprising a stout rigid finger spaced from and paralleling an adjacent one of said prongs, said finger being adapted to abut and ride slidably along an edge of said blank, and terminating at its outer end in a lateral bend functioning as a hook, all of said prongs being the same in length and have their pointed scribing ends disposed in a common plane, 20 said finger and hook being cylindrical in cross-section, said hook being directed toward the pointed ends of the prongs and being parallel to the handle and also at right angles to the axis of the finger, and the convex surface of the hook which is closest to and faces said one side of said handle being in substantially the same plane as the aforementioned common plane of said prongs so that it contacts one surface of the sheet metal blank while the pointed ends of the prongs ride against and score the other surface of said blank.
- 25 2. For use by sheet metal workers or one engaged in scribing and laying out an edge portion of a sheet metal blank to assist one in preparing and bending the scribed portion into an especially flanged end which is adapted to be tapped into an opening provided therefor in a trunk line; a measuring and scribing hand tool comprising a substantially rectangular block-like body having at least one flat side, an abutment finger having one end attached to said flat side and extending at right angles thereto and terminating at the outer end in a hook, said hook being adapted to slidably contact one surface of the sheet metal blank, and the portion of the finger adjacent to the hook being adapted to abut and ride along the very edge of the blank, said finger being cylindrical in cross section, and a plurality of rigid duplicate spaced parallel needle-like scribing prongs having corresponding ends attached to and projecting laterally from said one surface of the body, said prongs being in a plane which is common to all the prongs and also common to the plane of said finger, the free ends of said prongs all being pointed and terminating in a plane with each other and also in substantially the plane occupied by the surface of the hook which contacts the sheet metal blank when in use.
